SEALED POTENTIOMETER

Irving Gordy, Eatontown, N.J.

Application July 29, 1946, Serial No. 686,829.

7 Claims. (Cl. 201—55)

(Granted under the act of March 3, 1883, as amended April 30, 1928; 370 O.G. 757)

1

The invention described herein may be manufactured and used by or for the Government for governmental purposes without payment to me of any royalty thereon.

This invention relates to improvements in potentiometers, rheostats, and similar electrical resistance devices.

An essential object of this invention is to provide a potentiometer, rheostat, and the like, which is arranged and constructed so that all the electrical portions of the component are protected from deleterious substances present in the atmosphere, such as moisture, salt, dust, etc.

Another object of this invention is to provide a device of this character which has its electrical resistance means protected by sealing it hermetically in the resistor casing.

A more particular object of this invention is to protect and seal the resistance strip in the casing by the use of a thin metal diaphragm or disc mounted between said strip and an open end of the casing, said diaphragm being provided with bellows so as to allow for flexing of the diaphragm into engagement with the selected portion of the resistance strip.

These and various other objects and advantages are attained with this invention, as will become apparent from the following description, taken in connection with the accompanying drawings wherein the invention is shown in its preferred form, it being evident that other arrangements and forms of construction may be resorted to in carrying out the objects and purposes of this invention.

In the drawings:

Fig. 1 is a sectional view through the potentiometer, taken substantially along line 1—1 of Fig. 2.

Fig. 2 is partly a top view and partly a sectional view taken substantially on line 2—2 of Fig. 1.

The drawings illustrate my invention applied to a resistance mechanism which is shown in the form of a potentiometer, and it may likewise be applied to a rheostat and the like. This potentiometer as disclosed comprises a casing 10 which is substantially cup-shaped, and it is closed at the lower end 11 and has an opening 12 at the upper end, the casing being constructed of ceramic or other insulating material. Flange means 13 extends radially outward from the open end of the casing and is provided with apertures 14 for receiving screws 15 whereby the mechanism may be mounted for operation onto a panel 16 or the like. The screws 15 are shown as having their head ends held in a metal retaining ring 17 which is

therewith welded onto the panel 16, so as to extend from the ring through a washer 18 and through said flange means 13. The casing may also be soldered directly to the panel, where ease of replacement of the control is not important.

The resistance strip 21 is shown herein as including the wire coil 22 wound upon a suitable insulating member 23. The said member is mounted in the casing and may extend from the closed end 11 of the casing toward the opening, as shown herein, or it may be mounted so as to extend at a slant in the casing substantially parallel to the sealing means provided thereover.

A diaphragm or disc 24 of metal, such as Phosphor bronze, berillium, copper, etc., is mounted in the casing between the opening 12 and the resistance strip 21, and it is normally spaced from said strip, as indicated at the right-hand side in Fig. 1. This diaphragm is preferably conical in shape and it has its conical end 25 extending into the casing and mounted with sealing solder means 26 on a tubular member or part 27 extending inwardly from the end 11 of the insulating casing; as indicated in the drawing. The diaphragm is mounted to allow flexing or yielding movement in the casing and it is therefore provided with an annular bellows 28 around its outer or peripheral edge portion, said bellows being preferably integral with the diaphragm and being sealed to the casing around the open end 12 with a solder seal 29. The resistance strip is thus hermetically sealed in the casing beneath said diaphragm 24 with its bellows 28.

An operating member is shown herein as including a shaft 31 which extends rotatably through a collar 32 mounted in panel 16. From a head 33 at the inner end of the shaft extends an arm 34 provided at its free end with a shoe 35 which engages and is movable over the conical conductive diaphragm 24, in such a manner as to depress and flex the engaged part of the diaphragm into contact with the selected portion of the resistance strip 24 to include the desired amount of resistance, as indicated at the left-hand side of Fig. 1. A spring 37 between collar 32 and head 33 urges arm 34 with shoe 35 down to flex diaphragm 24 onto strip 21.

A terminal post 38 extends through the end 11 of the insulating casing, being solder-sealed therein, and it has a wire 39 connecting its inner end electrically with the diaphragm 24, while an electricity conductor 40 is connectable to its outer end. In the potentiometer, a pair of terminal posts 41 and 41' are likewise extended through the casing and solder-sealed therein, said posts having their

inner ends connected by wires 42 and 42' with the opposite ends of the resistance strip 21, while their outer ends are connectable to electricity conductors 43 and 43', in the usual manner. For the rheostat, one terminal post 41 is used.

I claim:

1. In a device of the class described, a casing having a casing wall and closed except for an opening at one end, electrical resistance means mounted within the casing, a metal sheet electrical contact member extending completely across the casing between said opening and said resistance means in juxtaposed spaced relation to the resistance means and having a flexible supporting and sealing portion adjacent the casing wall to secure it flexibly within the casing in spaced juxtaposed relation to the resistance means and protect and hermetically seal the resistance means within the casing between said metal sheet contact member and the closed end of the casing, terminal posts sealed in the casing wall between the flexible metal sheet contact member and the closed end of the casing and being each electrically connected at the inner end, one to the resistance means and another to the flexible metal sheet contact member, movable operating means supported in the open end of the casing, outwardly of said flexible metal sheet contact member, and operable upon said metal sheet contact member to force the portion thereof contacted by said operating means into contact with a selected portion of said resistance means, and thereby establish an electrical circuit between said terminal posts through the contact relation between the flexible metal sheet contact member and the resistance means.

2. In a device of the class described, an insulating casing having an inner wall and an opening at one end only, electrical resistance means mounted in the casing, a sheet metal flexible diaphragm mounted in the casing across the open end in juxtaposed spaced relation to the resistance means and positioned outwardly of said resistance means to seal the resistance means within the casing, said diaphragm having bellows means provided at its outer edge portion adjacent the inner wall of the casing and secured to the inner wall of the casing to protect and seal the resistance means hermetically therein, a plurality of electrical terminal posts extending through the casing wall in sealed relation thereto, an electrical connection between the inner end of one of said posts and said resistance means and another electrical connection between another of said posts and said diaphragm, and movable operating means supported outwardly of said diaphragm and extending into the casing, having a member thereon to contact with said diaphragm to flex said bellows and displace said sealing diaphragm into electrical contacting relation with a selected part of said resistance means to complete an electrical circuit between said terminal posts through the resistance means and said sealing diaphragm.

3. In a potentiometer and the like, an insulating casing having an opening in one end, means whereby to mount said casing, an electrical resistance strip mounted within the casing, a conical contact diaphragm of electrically conductive material extending across said opening within the casing with its apex extending toward the closed end of the casing, flexible supporting and sealing means formed at the peripheral edged portion of the diaphragm in supporting and sealing relation to the inner wall of the casing whereby the diaphragm is yieldably secured to the casing across

said opening and in spaced juxtaposed relation to the resistance strip to seal the resistance strip hermetically within the casing, three electrical terminal posts extending through the casing wall 5 in sealed relation thereto between the diaphragm and the closed end, one of said posts having its inner end electrically connected to said diaphragm and the other two posts each having its inner end electrically connected to one of the opposite ends of the resistance strip, and a movable operating member extending into the opening in the casing having diaphragm displacing pressure means thereon slideable on the outer portion of said diaphragm whereby to move said outer portion thereof into electrical contact with a selected part of said resistance strip.

4. In a device of the class described, a cup-shaped insulating casing having an opening at one end and means at said end whereby to mount the casing on a support, a resistance strip fixedly mounted within the casing, a conical metal electrically contacting and sealing diaphragm disposed across said opening in spaced juxtaposed relation to the strip and supported at its apex 20 within the casing, a bellows formed on the peripheral edge portion of the diaphragm and supported at its peripheral edge on the inner wall of the casing in sealing relation to said inner wall and said diaphragm whereby the latter is yieldably secured to the casing around the inner periphery of said opening to seal the resistance strip hermetically within the casing electrical terminal posts extending through the casing wall in sealed relation thereto between the closed end of the 25 casing and the diaphragm and bellows closure, one of said posts having its inner end electrically connected to said diaphragm and another post having its inner end electrically connected to the resistance strip, an operating shaft extending into said opening having an arm on its inner end, and pressure means carried by the arm between the diaphragm and said opening and movable on the diaphragm to flex a portion thereof into electrical contact with a selected part of the resistance strip.

45 5. In a potentiometer and the like, a substantially tubular ceramic casing closed at one end and having an opening at the other end, a curved resistance strip mounted within the casing, a conical metal electrical contact diaphragm member extending across the casing between the resistance strip and the opening, means supporting the conical diaphragm at its apex within the casing in spaced juxtaposed relation to the resistance strip, sealing and securing bellows means on the peripheral edge portion of said diaphragm and secured in sealing relation to the inner wall of the casing to yieldably secure the same to the casing and completely close said opening to protect and hermetically seal the resistance strip within the casing, a plurality of electrical terminal posts extending through the casing wall and sealed therein between the closed end of the casing and the conical diaphragm, an electrical connection between the inner end of one of said terminal posts 60 and said diaphragm and an electrical connection between the other electrical terminal posts and the opposite ends of the resistance strip, and movable operating means between the opening and the diaphragm, engaging the diaphragm at a point near its periphery to force the latter into electrical contact with a selected part of the resistance strip, for including a selected desired resistance of the resistance strip in the circuit between said terminal posts.

6. In a hermetically sealed variable resistance

device of the class described, an impervious cylindrical casing closed at one end and opened at its other end, a flexible resilient impervious electrical contact diaphragm member extending across the interior of the casing intermediate the closed end and its other end to form a hermetically sealed chamber within the casing between the diaphragm member and the closed end of the casing, a cylindrically curved resistance strip member concentrically arranged and fixed within the casing within the cylindrical chamber thereof having an electrical resistance contact surface fixed in closely spaced juxtaposed relation to the adjacent surface of said electrical contact diaphragm member, an electrical terminal post extending through the casing from the exterior to the interior of the hermetically sealed chamber electrically connected at one end to the resistance strip, a second terminal post fixed on said casing and electrically connected to said electrical diaphragm member, a rotary operating shaft concentrically journaled for rotative adjustment within the opened end of the casing, a resilient pressure means fixed on the shaft having a radially offset pressure shoe tensioned against the outer portion of the diaphragm and towards said re-

sistance strip for flexing the outer radial portion of the diaphragm toward the sealed chamber and into electrical contact with the adjacent portion of said resistance strip to establish an electrical resistance circuit within the hermetically sealed chamber and between said terminal posts through the resistance strip and said electrical contact diaphragm.

5 7. Apparatus as claimed in claim 6 including 10 flexible bellows means formed at the periphery of said diaphragm adjacent the interior wall of the casing to provide increased flexibility between the outer portion of the diaphragm and its sealed and connected portion with the inner portion of the casing.
